(57) **CLAIM**

I claim the ornamental design for a baseball cap with football helmet accessories, as shown and described.

DESCRIPTION

FIG. 1 is a front perspective view of a baseball cap with football helmet accessories, showing my new design;
FIG. 2 is a bottom perspective view thereof;
FIG. 3 is a front elevational view thereof;
FIG. 4 is a rear elevational view thereof;
FIG. 5 is a right-side elevational view thereof;
FIG. 6 is a left-side elevational view thereof;
FIG. 7 is a top plan view thereof; and,
FIG. 8 is a bottom plan view thereof.
The broken lines in the figures represent stitching, and are part of the claimed design.
